INVENTOR

United States Patent Office.

JACOB LOUIS KUECHLER, OF READING, PENNSYLVANIA, ASSIGNOR TO
ORR, PAINTER & CO., OF SAME PLACE.

Design No. 4,815, dated April 18, 1871.

DESIGN FOR A COOKING-STOVE.

The Schedule referred to in these Letters Patent and making part of the same.

To all whom it may concern:

Be it known that I, JACOB LOUIS KUECHLER, of Reading, in the county of Berks and State of Pennsylvania, have invented and produced a new and original Design for Cook-Stoves, of which the following is a specification.

The nature of my invention is fully represented in the accompanying photographic illustrations, to which reference is made.

On a raised scroll ornament, *a*, on each side plate *A* of the stove, above the oven-door, is the title of the stove, "Morning Light;" and at the bottom edge of the plate, on a raised panel, *B*, are the name and place of the manufacturing firm, "ORR, PAINTER & CO., Reading, Pa."

The title of the stove is also on the front fire-plate *C*, immediately above the fire-doors *D D*.

On the raised panel *B'* of the oven-doors *D'* is an elliptical raised ornament, *a*, in the center, surrounded by swelled ornaments *b b* and *d d*, around which is the wreath *E*, which spreads out over the surface of the panel and approximates to the square form of the latter.

The stem of the wreath is formed of scrolls *ffff*, which meet together and form an ellipsis.

The fire-doors *D D* and the end doors *D''* are in their general design like the oven-doors *D' D'*.

The doors *D'' D''* at the sides of the stove, beneath the hearth-plate, have a central slightly-elliptical ornament, *g*, surrounded by a leafed ornament, *h*, of elliptical formation, which is surrounded by a wreath, *E'*, that spreads out over the face of the door, and is surrounded by a bead, *K*, at the edges of the panel.

The front plate *F*, near its lower edge, has an ornament, *m*, in the sunk panel *I*.

The stiles *G G* of the fire-front *H* have vertical ornaments *ll*.

What I claim as my invention is—

The design for cook-stoves, as shown and described.

In testimony whereof I have hereunto set my hand and seal this day of March, 1871.

JACOB LOUIS KUECHLER. [L. S.]
